FLUORESCENT LIGHTING FIXTURE

Adolph B. Bechaud, Fond du Lac, Wis., assignor
to Scientific Lighting, Inc., Fond du Lac, Wis.,
a corporation of Wisconsin

Application October 22, 1942, Serial No. 462,911

3 Claims. (Cl. 240—78)

The invention relates to lighting fixtures and more particularly to lighting fixtures adapted for use with fluorescent bulbs.

The general object of the invention is to provide a novel lighting fixture of the above general character adapted to be constructed largely of lightweight dielectric material such as wood, plastics or other non-metallic materials, which is simple and relatively inexpensive to manufacture, attractive in appearance and sufficiently rugged to withstand the hard usage to which lighting fixtures are commonly subjected in industrial installations.

Another object is to provide a lighting fixture of novel and advantageous construction having the electrical apparatus and supporting framework assembled as a unit independently of the reflector, thus permitting the use of a reflector of lightweight, preferably non-metallic material, and enabling such reflector to be mounted on the supporting frame structure for convenient removal to facilitate cleaning or replacement thereof.

A further object is to provide a lighting fixture of the above character in which the electrical apparatus units are electrically interconnected for grounding independently of the supporting framework.

Other objects and advantages of the invention will become apparent from the following detailed description of the preferred embodiment illustrated in the accompanying drawing in which:

Figure 1 is a perspective view of a fluorescent lighting fixture embodying the features of the invention.

Fig. 2 is a fragmentary top view of the fixture.

Fig. 3 is a transverse sectional view taken along the line 3—3 of Fig. 2.

Fig. 4 is a longitudinal sectional view taken along the line 4—4 of Fig. 2.

While I have shown, and will hereinafter describe a preferred form of the invention, it is to be understood that various changes may be made in the form, construction and arrangement of the parts without departing from the spirit and scope of the invention as defined by the appended claims.

Referring to the drawing, the lighting fixture in its preferred form comprises a lightweight, elongated rigid frame structure 5 with which are assembled the various electrical apparatus units such as a ballast unit 6 and a pair of socket supporting units 7, and to which a suitable reflector 8 is removably attached. Con-

ventional sockets 9, carried by the units 7, are arranged to hold one or more fluorescent bulbs or lamps B in predetermined, spaced relation with respect to the reflector 8. The various electrical elements are suitably interconnected for supplying operating current to the lamps B and the units themselves are interconnected for grounding purposes independently of the frame structure.

10 While the frame 5 may be of any desired form, the preferred form shown in the drawing lends itself particularly well to construction from lightweight dielectric material such as wood, plastics or other non-metallic materials. Preferably, the frame 15 comprises a pair of relatively thin elongated side members 11 and 12 arranged in side-by-side relation and connected at their ends by end members 13 and 14 to form a boxlike rectangular frame structure. The side members 20 may be tapered slightly from the center toward opposite ends to reduce the weight of the frame without sacrificing strength or longitudinal rigidity. Panels 15 of plywood or like material, extending between the side members and rabbeted 25 or otherwise securely attached thereto, act to hold the frame members in fixed relation and additionally serve in cooperation with the side members to define downwardly opening channel-shaped chambers at each end of the frame for 30 housing electrical equipment.

The frame structure is further strengthened by relatively thick cross members 16 connected between the side members at opposite ends of the frame. These cross members also provide anchoring means for hook devices such as eyebolts 17 by which the fixture may be suspended from chains or the like attached to the ceiling or other suitable support. The eyebolts 17 are arranged to project through the cross members 16 and are 35 anchored thereto in any suitable way as by nuts 18 threaded thereon. In the particular construction illustrated, the threaded section of the eyebolt is extended substantially below the lower edge of the frame structure for attachment of the reflector as will be described hereinafter.

The ballast unit 6 may be of any suitable and well-known type adapted for operation with the particular fluorescent lamp or lamps to be installed in the fixture. As herein shown the unit 50 is of generally rectangular shape adapted to fit between the frame members 11 and 12 and to be supported thereon substantially centrally of the frame, the panels 15 being terminated at each side of the center of the frame to provide a recess for the reception of the unit.

For supporting the unit, a pair of transversely disposed angle bars 19 are connected between the side members of the frame suitably spaced apart to permit the unit to rest on the inwardly facing horizontal flanges as shown in Figs. 2 and 4. The side members are notched to receive the angle bars so that the outer surfaces thereof are substantially flush with the lower edges of the side members. Any suitable means such as screws 20 may be utilized to attach the bars to the frame structure.

The electrical apparatus units 7, as herein shown, are alike, each comprising a boxlike metal housing including a relatively shallow flanged base plate 21 with an interfitting cover 22. In the particular fixture illustrated each unit is fitted with two of the lamp sockets 9 and with a socket for a conventional starter 23. The lamp sockets, which are of the type commonly used in fluorescent lighting fixtures, are preferably attached to the cover 22 and are arranged to project downwardly therethrough. When the fixture is designed to accommodate a plurality of fluorescent lamps, the sockets of each unit are suitably spaced apart transversely of the fixture to provide the required spacing between the lamps.

The starter 23 is preferably located so as to project from the cover 22 between the two lamp sockets 9 and is desirably mounted in a socket to permit convenient removal for replacement or repair. It will be understood, of course, that the number of lamp sockets provided in the units 7 is dependent entirely upon the number of fluorescent lamps to be accommodated in the fixture. It will also be understood that the starter socket and associated starter may be omitted from one unit when the fixture is to be equipped with a single lamp.

The units 7 are arranged transversely of the frame 5 at opposite ends thereof and are spaced apart to position the sockets 9 for coaxing with the opposite ends of the fluorescent lamps B. Thus, the two lamps are held in parallel relation and extend longitudinally of the fixture. The lower side edges of the frame members 11 and 12 are recessed for the reception of the units so that the bottom of the cover 22 lies substantially flush with the lower edges of the frame members. Any suitable means such as wood screws 25 may be utilized to attach the base plate 21 of the unit to the frame structure while the cover in turn may be secured to the base by frictional engagement or by suitable locking screws as desired.

The mounting of the electrical apparatus units 7 and the ballast unit supporting bars 19 flush with the lower edges of the frame members, as above explained, provides a flat surface for engagement by the reflector 8. The reflector illustrated is accordingly formed with a substantially flat central section adapted to seat against the side members and the end members of the frame. Suitable apertures are provided at opposite ends of the central section to accommodate the projecting sockets 9 and the starter 23 which, as before explained, are assembled as a unit with the frame structure. Additional apertures are provided for receiving the projecting ends of the eye bolts 17, and wing nuts 26 threaded thereon may be utilized to hold the reflector in assembled relation with the frame. Thus, by simply removing the lamp B from the sockets and unscrewing the wing nuts the reflector may be detached from the fixture. Moreover, since the reflector is not required to support any of the electrical elements

of the fixture it may be made of relatively lightweight material such as thin sheet metal, plywood, plastics, etc.

The lamp sockets, starter and ballast units 6 are interconnected by suitable conductors 30, while conductors 30' leading out from one of the units 7 and through an opening in the panel 15 at one end of the frame connect the electrical apparatus with a source of current. A metallic channel member 31 attached to one of the side members 11 of the frame extends between the two units 7 and forms a conduit for the conductors 30, the conductors being confined therein by split rivets 32 entered in suitable apertures in the member. At each end, the conduit member is provided with a flat extension or tongue 33 adapted to be attached to the metallic housings of the respective units 7 by screws or other suitable means to provide a ground connection therebetween. The conduit member is electrically connected with one of the angle bars 19 as by a contact strip 34, and the angle bar, in turn, is electrically connected with the housing of the ballast unit 6, thus providing a common ground connection for all of the electrical apparatus of the fixture independently of the frame structure. This is a safety feature of substantial importance where the supporting framework is to be constructed of non-conducting material such as wood.

It will be apparent from the foregoing that the invention provides a fluorescent lighting fixture of novel and advantageous construction. The supporting framework of the fixture, together with the electrical elements, are assembled as a unit to which the reflector may be detachably connected. The reflector, accordingly, is not required to support any of the electrical elements and may, therefore, be constructed of lightweight material. Moreover, it may be readily removed for cleaning or replacement. The frame structure, as well as the reflector, may be made of non-metallic materials and safe operation is insured by the provision of an effective ground connection between the various electrical elements independently of the frame structure. In general, it will be observed that the lighting fixture thus provided is light in weight, attractive in appearance and yet sufficiently rugged to withstand hard use.

I claim as my invention:

1. A fluorescent lighting fixture having, in combination, a frame of lightweight dielectric material adapted to support the electrical elements of the fixture and a reflector, said frame comprising a pair of elongated side members arranged in spaced parallel relation, relatively wide cross members connecting the side members at opposite ends, panel members assembled with said side members to hold the frame rigid, spaced angle bars connecting between said side members operative to support a ballast unit substantially centrally of the frame, said side members being notched adjacent opposite ends for the reception of a boxlike electrical apparatus housing having projecting sockets for holding fluorescent lamps, and means anchored to the cross members for suspending the fixture, said suspending means being extended through said cross members for detachably connecting the reflector to the frame.

2. A fluorescent lighting fixture having an elongated frame of lightweight dielectric material and a reflector detachably secured to the underside of the frame, said frame comprising

spaced parallel side members, cross members connecting said side members at opposite ends, panel members disposed between the side members to define therewith a rigid channel-shaped structure, electrical apparatus units each including a housing carrying a depending lamp socket supported at opposite ends of the frame, said side members being notched to hold said units with the underside of the housings flush with the lower edge of the side members, hook members each having a threaded portion extending through said panels and attached to said cross members to support the fixture, said hook members having their ends projecting below the lower edges of the side members and through said reflector, and nuts threaded onto said projecting ends of the hook members to hold the reflector in assembled relation with the frame.

3. A fluorescent lighting fixture having, in combination, a frame comprising elongated parallel side members connected at each end by

relatively short cross members to form a rigid rectangular structure, said members being constructed of lightweight dielectric material, electrical apparatus units mounted adjacent opposite ends of said frame each including a housing substantially wider than said cross members and carrying a projecting lamp socket, the side members of the frame being notched for the reception of said housings whereby each unit is held with the bottom of its housing substantially flush with the bottom edges of the side members and with the socket extending below the side members, said units being spaced apart to position the sockets for cooperation with the opposite ends of a fluorescent lamp, a reflector apertured to receive said lamp sockets and means carried by the cross members of the frame for holding said reflector against the underside of said frame.
